UNITED STATES PATENT OFFICE.

JEDDY D. NIXON, OF HOUSTON, TEXAS, ASSIGNOR TO TEXAS IRON WORKS SALES CORPORATION, OF HOUSTON, TEXAS, A CORPORATION OF TEXAS.

ROD HANGER.

Application filed March 29, 1926. Serial No. 98,313.

This invention relates to new and useful improvements in a rod hanger.

One object of the invention is to provide a device of the character described specially designed for the purpose of suspending the pump rods of a well pump in the derrick, and is of such construction that the rods may be readily attached to the hanger, as pulled from the well and as readily detached therefrom, 10 as made up in letting the same down into the well.

Another object of the invention is to provide a novel type of rod hanger by means of which the rods may be suspended in the derrick in the order in which they are separated, as broken up, and may be reunited, in letting them back into the well, in the order of their original positions in the completed, or made up pump sucker rod.

20 A further feature of the invention resides in the provision of a hanger which is of very simple construction, may be cheaply and easily produced and through which the pump rods may be easily and expeditiously handled 25 in pulling the same from, or letting the same down into, a well bore.

With the above and other objects in view this invention has particular relation to certain novel features of construction, operation 30 and arrangement of parts, an example of which is given in this specification and illustrated in the accompanying drawings, wherein:

Figure 1 shows a horizontal sectional view 35 of a derrick, showing a plan view of the improved type of rod hanger mounted therein.

Figure 2 shows a fragmentary vertical sectional view thereof, showing said rod hanger in section.

40 Figure 3 shows an enlarged plan view of the hanger, and Figure 4 shows an enlarged side elevation thereof, partly in section.

Referring now more particularly to the drawings, wherein like numerals of reference 45 designate similar parts in each of the figures the numeral 1 designates the derrick, as a whole, which is of conventional construction. In the derrick there is a transverse I-beam 2 whose ends are supported on the cross beams 50 3, 3, forming part of the derrick. The I-beam 2 is preferably disposed with its web in horizontal position and its end flanges resting upon the beams 3 and disposed vertically. The beam 2 is disposed in the derrick to one 55 side of, and above, the well 4 being pumped.

The complete hanger has a plurality of units, as 5, each slidably mounted on the I-beam 2. Each unit 5 includes an inverted U-shaped bracket 6 which rests on the beam 2 and whose arms 7, 7, embrace said beam and 60 whose free ends are inwardly turned to form retaining lugs 8, 8, which engage underneath the lower flanges of the I-beam 2.

Formed integrally with each bracket 6 there is a bar 9, one end of which extends out 65 beyond the corresponding arm 7 of said bracket and is formed into a hook 10 provided with a V-shaped notch 11, forming a rod engaging jaw. Pivoted to the bar opposite said jaw there is a dog 12 whose free end is serrated, or toothed, and behind this dog the bar 9 carries the stop 13, against which said dog engages, or rests, when in inactive position.

Swung from the respective cross beams 3 are the U-shaped hangers 14, 14, the upper 75 ends of whose arms are formed with hooks which engage over said beams and a wide board 15, forming a platform, has its ends supported by said hangers 14. This platform is provided for the support of a workman in 80 the derrick.

In pulling the rods, as 16, each rod is unscrewed from the one beneath and is then elevated by a rod elevator 17, which is engaged around the upper end of the rod and is manipulated by the cable 18 in the usual way. When the rod is elevated to the required height, as illustrated in Figure 2, it is grasped by the workman on the platform 15 and swung into the notch 11 and the dog 12 then 90 swung into engagement with said rod to grip and hold the same in said notch. The elevator is then released for engagement with the next rod to be elevated. The unit 5, with the rod suspended therefrom is then grasped by 95 said workman and moved over on the beam 2, out of the way, and another empty unit 5 is moved into readiness to receive the next rod elevated and so on until all of the rods are 100 swung from the hanger, as illustrated in Figure 1.

When it is desired to make up the rods again to let them down into the well the last rod elevated will be the first one to be lowered. In order to accomplish this the elevator 17 is 105 engaged around the rod above the jaw 11 and the rod is pulled upwardly and this will throw the dog 12 back against the stop 13 into released, or inactive position and the rod is then released from the jaw 11 and lowered 110

and attached to the pump. The other rods in the rod hanger are then in like manner engaged by the elevator 17 and released from the rod hanger, as explained and lowered in the reverse order of their elevation and coupled together, each rod being coupled to the one beneath it, in lowering them into the well. Each rod has an internally threaded box 19 on one end and an externally threaded pin 20 on the other end, the pin of one rod being adapted to screw into the box of the rod above. It is desirable that the pin of any particular rod be screwed back into the same box from which it was unscrewed, in order to form a perfect fit, inasmuch as each pin is mated with its particular box and might not mate or fit perfectly with some other box. It is therefore necessary that rods be stored on the hanger in the order in which they are separated so that they may be returned and made up in their original order, as let down into the well. This is easily accomplished with the type of hanger herein described, and furthermore the suspended rods will not become entangled, or twisted together, thus con-
20 ducing to ease in handling. The upper ends of the rods, suspended from the hanger, ex-
25 tend some distance above the hanger so that the conventional type of elevator, adapted to engage round rods, may be easily engaged
30

around the round portion of the rod imme-
diately above the hanger, in all of these re-
spects the type of hanger herein described
constitutes an improvement over rod hangers
now in common use.

35

What I claim is:—

1. In a derrick, the combination with oppo-
sitely disposed end supports of a transverse
I-beam whose ends are supported on said end
supports, a plurality of rod engaging means
40 of said beam each rod engaging means in-
cluding a U-shaped bracket having depending
arms which embrace said beam, the free ends
of said arms being inwardly turned forming
retaining means said bracket being slidable
lengthwise on said beam.

2. The combination with oppositely dis-
posed end supports of an I-beam whose ends
rest on said supports said beam being dis-
posed with its web in horizontal position and
its flanges disposed vertically, of rod engag-
ing means movable lengthwise on said beam,
each engaging means including an inverted
45 U-shaped bracket on said beam with its side
arms embracing said beam and with the free
ends of said arms inwardly turned and form-
ing retaining means.

In testimony whereof I have signed my
name to this specification.

JEDDY D. NIXON.
